CLAIM

The ornamental design for a hair clipper housing, as shown and described.

DESCRIPTION

FIG. 1 shows a perspective view of a first preferred embodiment of the present design.

FIG. 2 shows a right view of the first preferred embodiment of the present design.

FIG. 3 shows a top view of the first preferred embodiment of the present design.

FIG. 4 shows a front view of the first preferred embodiment of the present design.

FIG. 5 shows a bottom view of the first preferred embodiment of the present design.

FIG. 6 shows a left view of the first preferred embodiment of the present design.

FIG. 7 shows a rear view of the first preferred embodiment of the present design.

FIG. 8 shows a perspective view of a second preferred embodiment of the present design.

FIG. 9 shows a right view of the second preferred embodiment of the present design.

FIG. 10 shows a top view of the second preferred embodiment of the present design.

FIG. 11 shows a front view of the second preferred embodiment of the present design.

FIG. 12 shows a bottom view of the second preferred embodiment of the present design.

FIG. 13 shows a left view of the second preferred embodiment of the present design; and,

FIG. 14 shows a rear view of the second preferred embodiment of the present design.

The broken line showing of the switch hole, contact hole, connection interface and housing interior is for illustration purposes only and forms no part of the claimed design.
